UNITED STATES PATENT OFFICE.

WILHELM OVERDICK, OF BROOKLYN, NEW YORK.

LOCK HAVING AN INNER AND AN OUTER HANDLE ROTATABLE INDEPENDENTLY OF EACH OTHER.

Application filed February 18, 1924. Serial No. 692,456.

The present invention relates to door locks in which the locking means are operated in a different way by two arms in engagement therewith, each of these arms being actuated independently of the other by one of the two handles mounted to turn independently of one another, for the purpose of automatically preventing opening of the door by means of the outer handle after it has been shut by means of the inner handle, until the latter has again been depressed. Such locks provided with devices for indicating whether a room is vacant or occupied, are used for lavatories, ship cabins, etc., for the purpose of making unnecessary the use of separate locking devices equipped with such indicators. Locks of this kind, as made hitherto, are of relatively complicated construction which offsets the advantage obtained by the elimination of a separate locking device; furthermore, doors equipped with these locks cannot be shut by mere pushing or slamming like doors with ordinary locks, and it is necessary to fully depress the handle to lock the door from either side.

In the present lock these defects are eliminated. Its construction is simple and permits the use of a latch bolt having the usual inclined surface, and which will be pushed back and snap into place when the door is pushed or slammed shut.

Unlike some of the locks of this type, the present lock has only one latch bolt which moves lengthwise in the usual manner. The moving of an inner arm by means of a handle against a hook rigidly secured to the latch bolt will, in every case, cause the latter to move back, while the outer arm will move the latch bolt back in a similar manner only in case a second hook pivoted on the latch bolt is in the path of this arm. The pivoted hook may be moved out of the path of the arm by the depression of the inner handle which causes a lifter, which engages the hook, to slide transversely of the latch bolt.

In the accompanying drawings

Figure 1 is a side elevation of the lock, as seen from the outside, with the outer cover plate removed, the lock being in the normal position.

Figure 2 is a similar view showing the latch bolt moved back by the inner arm.

Figure 3 is another view similar to Fig-

ures 1 and 2, showing the latch bolt moved to its locking position, by means of the inner handle.

Figure 4 is a vertical section on line 4—4 of Figure 1.

Figure 5 is a horizontal section on line 5—5 of Figure 1.

Figure 6 is a partial end view of the casing.

Figure 7 is a partial view of the locking plate.

Figure 8 is a view similar to Figure 1 showing the position of the parts at the moment when the pivoted hook is released.

Figures 9 and 10 are partial side elevations showing the indicating device in both positions.

The housing of the lock comprises the usual two parallel side walls 1, 2 and an end wall 3 connecting the forward edges of plates 1 and 2. The latch bolt 4 of the lock has at its outer end an inclined surface 5 and is provided with reinforcing plates 6 for the purpose of increasing the width of the inclined surface. The reinforcing plate 6 is guided in a slot in plate 2. The inner portion of the latch bolt which is flat has a bottom shoulder 7 and a rearward extension 8 of half the thickness of the wide portion of the latch bolt and extending along the outer wall 2. Portion 8 has a lateral offset at 9 and to the rear thereof a downward projection forming a hook 10. The hook 10 is provided at its lower end with a guide flange 11 extending through a slot in the inner wall 1 of the housing and serving to guide the latch bolt at its inner end.

A lug 13 is provided at the top of the latch bolt 4 which may project a certain distance through opening 14 in end wall 3, said opening being located near the inner wall of the housing and forming an extension of opening 15 for the latch bolt. A hook 16 is pivoted to the outer side of lug 13 on a horizontal pin 17, the shank 18, of the hook 16 extending rearwardly along the outer wall 2 above the portion 8 and being provided at its end with a hook 19 extending in front of hook 10 which is offset inwardly.

Arms 20, 21 on disks 22, 23 are adapted to swing in the path of hooks 10 and 16 respectively. Disks 22, 23 have each a short stud integral therewith, which extends

through a suitable opening in the housing. The disks 22, 23 are free to swing and are turned by means of the handles 25, 26 the square end portions of which are inserted 5 into a square hole 24 in each of the disks 22, 23.

Each disk has a rearward projection 27 against which bear springs 28, 29 respectively which hold the projections 27 from 10 below against a stop 30 when the lock is at rest.

The inner disk 22 has on its front portion a short lifting arm 31 on which rests the lower end of the lifting slide 32 which is 15 guided by a longitudinal projection 33 engaging in a vertical slot 34 in the inner wall 1, and which extends upwardly between this wall and the horizontal lock portions 8 and 18 located above each other, and 20 which has an offset 35 toward the rear of the housing.

At the lower end of this offset the slide 32 is provided with a vertically narrow lifting lug 36 which projects into the space 25 between the hook portions 8 and 18. Between the lug and a reinforced upper portion 37 of the slide 32 is formed a recess 30 in which the hook 16 can swing freely. The lower shoulder of portion 37 is engaged at one end by a suspended pawl 38 pivoted on 35 studs of its hub 39 in opposite holes of walls 1 and 2 of the housing. A spring 40 urges pawl 38 against the portion 37 of slide 32. The slide itself is urged down by a spring 41.

When the outer handle 25 is depressed and the disk 23, which is connected to the handle, is thereby turned and the arm 21 swung back, the latter will engage hook 10 40 and the latch bolt will be withdrawn against the action of spring 42 engaging the latch bolt at its outer end. When the handle is released, the latch bolt will move back to its former position. During these operations 45 the lifting slide 32 and the pivoted hook 16 have not been moved out of the lower position shown in Figure 1 which is the position at rest.

When the inner disk 22 is rotated by 50 means of the inner handle, arm 20 will engage the rigid hook 10 of the latch bolt and cause the latch bolt to move back; simultaneously the lug 31 will lift the slide 32 as shown in Figure 2. The lug 36 will cause the pivoted hook 16 to swing upward 55 and the pawl 38, which previously had been swung toward the front end of the lock, will snap over the edge of portion 37.

After the door has been shut and the 60 inner handle is released, the end portion of the latch bolt 4 will enter the rectangular opening 43 in the locking plate 44 of the door frame. The locking plate 44, however, has no opening in alignment with the lug 13 and the advance of the latch bolt is

limited by the engagement of lug 13 with locking plate 44.

In case the inner handle is released while the door is open, the latch bolt will project somewhat further beyond the end plate 3, 70 there being nothing in the path of lug 13. This will cause a release projection 45 at the upper edge of hook 16 to force pawl 38 out of its locking position, as shown in Figure 8, whereby the slide 32 is released and 75 allowed to drop down with the hook 16 under the action of the spring.

As may easily be seen the door cannot be opened by means of the outer handle after it has been shut and the latch bolt been 80 pulled back by means of the inner handle until the inner handle has again been operated. In order to indicate this locked condition to persons inside and outside the door, an indicator plate 47 is provided on 85 each side, extending behind cover plates 46 and having a vertical movement. Each plate 47 is provided with a horizontal extension 48 secured in a rectangular opening 49 in portion 37 of slide 32 and extending through 90 suitable slots in the door and the walls 1 and 2 of the housing. The indicator plates thus move up and down in unison with the slide 32 and alternately display the words "open" and "vacant" through a suitable 95 opening in cover plates 46.

To permit, in certain exceptional cases, opening of the door from the outside after it has been locked from the inside, the hub portion 39 of the pawl 38 may be provided 100 with a square hole so that the pawl can be swung out of its locking position by means of a square key inserted into this hole. Pawl 38 is preferably provided with an arm 50 limiting the rotation of the pawl when the 105 latter is turned by means of a key.

The inclined surface at the forward end of the latch bolt is provided on the outer side of the bolt, as required for doors opening inwardly. On doors opening outwardly 110 this inclined surface must, of course, face inwardly. The inclined surface permits of shutting the door by merely pushing or slamming it, without requiring the depression of a handle. When the door has been 115 shut in this manner, either from the inside or the outside, the outer handle is not rendered inoperative. This will only be the case when the inner handle has been depressed.

While I have herein described and illustrated one practical embodiment of my present improvements, it is nevertheless, to be understood that the essential features thereof might also be incorporated in various other alternative structures, and I therefore, reserve the privilege of resorting to all such legitimate changes in the form, construction and relative arrangement of the several elements as may be fairly considered 130

within the spirit and scope of the appended claims.

Claims:

1. In a lock, inner and outer independently rotatable handles, a lock bolt having a rearward extension, a part movably connected at one of its ends with the bolt, members fixed to each of the handles and cooperating respectively with said bolt extension and with said part whereby, upon the rotation of one of said handles the lock bolt is retracted, a slidable member cooperating with said part, and said bolt retracting member on the latter handle having a part cooperating with said slidable member when the bolt is retracted to actuate the same and move said movable part on the latch bolt out of the path of movement of the member on the other lock handle. 15
  2. In a lock, inner and outer independently rotatable handles, a lock bolt, a part pivotally mounted at one of its ends upon the lock bolt and having its other end normally positioned in parallel relation with the bolt at one side thereof, an actuating arm fixed to each handle member and adapted to cooperate with the bolt and with said part respectively to retract the bolt, a member slidably mounted in the lock case and supporting said pivoted part in its normal position, and said handle having the arm engaging the bolt being further provided with means for actuating said slidable member as the bolt is retracted to move said pivoted part out of the path of movement of the actuating arm on the other handle member. 20
  3. In a lock, inner and outer independently rotatable handles, a lock bolt, a part pivotally mounted at one of its ends upon the lock bolt and having its other end normally positioned in parallel relation with the bolt at one side thereof, an actuating arm fixed to each handle member and adapted to cooperate with the bolt and with said part respectively to retract the bolt, a member slidably mounted in the lock case and supporting said pivoted part in its normal position, and said handle having the arm engaging the bolt being further provided with means for actuating said slidable member as the bolt is retracted to move said pivoted part out of the path of movement of the actuating arm on the other handle member, and means for releasably retaining the slidable member in the latter position. 25
  4. In a lock, inner and outer independently rotatable handles, a lock bolt, a part pivotally mounted at one of its ends upon the lock bolt and having its other end normally positioned in parallel relation with the bolt at one side thereof, an actuating arm fixed to each handle member and adapted to cooperate with the bolt and with said part respectively to retract the bolt, a member slidably mounted in the lock case and supporting said pivoted part in its normal position, and said handle having the arm engaging the bolt being further provided with means for actuating said slidable member as the bolt is retracted to move said pivoted part out of the path of movement of the actuating arm on the other handle member, a pivoted pawl mounted in the lock case and cooperating with said slide to retain the same in the latter position, and said pivoted part on the lock bolt having means to engage said pawl and release the slide in the movement of the lock bolt to its fully projected position. 30
- slidably mounted in the lock case and supporting said pivoted part in its normal position, and said handle having the arm engaging the bolt being further provided with means for actuating said slidable member as the bolt is retracted to move said pivoted part out of the path of movement of the actuating arm on the other handle member, and means for releasably retaining the slidable member in the latter position, said pivoted part having a shoulder adapted to engage the latter means and release the slidable member in the return of the lock bolt to its normal position. 35
5. In a lock, inner and outer independently rotatable handles, a lock bolt, a part pivotally mounted at one of its ends upon the lock bolt and having its other end normally positioned in parallel relation with the bolt at one side thereof, an actuating arm fixed to each handle member and adapted to cooperate with the bolt and with said part respectively to retract the bolt, a member slidably mounted in the lock case and supporting said pivoted part in its normal position, and said handle having the arm engaging the bolt being further provided with means for actuating said slidable member as the bolt is retracted to move said pivoted part out of the path of movement of the actuating arm on the other handle member, and means for releasably retaining the slidable member in the latter position, said lock bolt having a lug adapted to engage a strike plate and limit the projection of the bolt from the lock housing when the door is closed, and said pivoted part having a shoulder adapted to engage said slide holding means and release the slide in the further projection of the bolt to its normal position after the door is opened. 40
6. In a lock, inner and outer independently rotatable handles, a lock bolt, a part pivotally mounted at one of its ends upon the lock bolt and having its other end normally positioned in parallel relation with the bolt at one side thereof, an actuating arm fixed to each handle member and adapted to cooperate with the bolt and with said part respectively to retract the bolt, a member slidably mounted in the lock case and supporting said pivoted part in its normal position, and said handle having the arm engaging the bolt being further provided with means for actuating said slidable member as the bolt is retracted to move said pivoted part out of the path of movement of the actuating arm on the other handle member, a pivoted pawl mounted in the lock case and cooperating with said slide to retain the same in the latter position, and said pivoted part on the lock bolt having means to engage said pawl and release the slide in the movement of the lock bolt to its fully projected position. 45

7. In a lock, inner and outer independently rotatable handles, a lock bolt, a part pivotally mounted at one of its ends upon the lock bolt and having its other end normally positioned in parallel relation with the bolt at one side thereof, an actuating arm fixed to each handle member and adapted to cooperate with the bolt and with said part respectively to retract the bolt, a member slidably mounted in the lock case and supporting said pivoted part in its normal position, and said handle having the arm engaging the bolt being further provided with means for actuating said slidable member as the bolt is retracted to move said pivoted part out of the path of movement of the actuating arm on the other handle member, said bolt having a lug thereon to engage a strike plate when the door is closed and limiting the projecting movement of the bolt, a pivoted pawl mounted in the lock case and cooperating with said slide to retain the same in the latter position, and said pivoted part on the lock bolt having means to engage said pawl and release the slide in the movement of the lock bolt to its fully projected position, said pawl having means whereby the same may be manually operated independently of the lock bolt to release the slide.

8. In a lock, inner and outer indepen-

dently rotatable handles, a lock bolt, a part pivotally mounted at one of its ends upon the lock bolt and having its other end normally positioned in parallel relation with the bolt at one side thereof, an actuating arm fixed to each handle member and adapted to cooperate with the bolt and with said part respectively to retract the bolt, a member 35 slidably mounted in the lock case and supporting said pivoted part in its normal position, and said handle having the arm engaging the bolt being further provided with means for actuating said slidable member 40 as the bolt is retracted to move said pivoted part out of the path of movement of the actuating arm on the other handle member, said bolt having a lug thereon to engage a 45 strike plate when the door is closed and limiting the projecting movement of the bolt, a pivoted pawl mounted in the lock case and cooperating with said slide to retain the same 50 in the latter position, and said pivoted part on the lock bolt having means to engage said 55 pawl and release the slide in the movement of the lock bolt to its fully projected position, said pawl having means whereby the same may be manually operated independently 60 of the lock bolt to release the slide, and indicating means carried by and movable with said slide and visible from the opposite sides of the lock case.

WILHELM OVERDICK.
